UNITED STATES PATENT OFFICE.

JOSEPH FRANK, OF PITTSTON, PENNSYLVANIA.

INSECTICIDE-DISTRIBUTEER.

1,140,453.

Specification of Letters Patent. Patented May 25, 1915.

Application filed September 30, 1914. Serial No. 864,325.

To all whom it may concern:

Be it known that I, JOSEPH FRANK, a citizen of the United States, residing at Du-
5 pont, Pittston, in the county of Luzerne
and State of Pennsylvania, have invented
certain new and useful Improvements in
Insecticide-Distributers, of which the fol-
lowing is a specification, reference being had
to the accompanying drawings.

10 This invention relates to an improved in-
secticide distributor and has for its primary
object to provide a device of this character
which may be conveniently strapped or
otherwise secured upon the body of the op-
erator, said device including means whereby
15 the insecticide may be sprayed or otherwise
distributed under pressure upon the foliage.

The invention has for a more particular
object to provide improved means for
20 mounting a force pump within the tank or
reservoir, and certain novel structural fea-
tures in the pump whereby access may be
readily had to the parts thereof for the pur-
pose of cleaning or repairing the same.

25 The invention has for a further general
object to produce a device of the above char-
acter which is comparatively light in weight,
highly serviceably and convenient in actual
use and one which may be produced at small
30 manufacturing cost.

With the above and other objects in view,
my invention consists in the novel features
of construction, combination, and arrange-
35 ment of parts to be hereinafter more fully
described, claimed, and illustrated in the ac-
companying drawings, in which,

Figure 1 is a perspective view illustrating
the preferred embodiment of my invention.
Fig. 2 is a vertical section through the same.
40 Fig. 3 is a section taken on the line 3—3 of
Fig. 2. Fig. 4 is an elevation illustrating
the attaching means. Fig. 5 is an enlarged
vertical section of the lower end portion of
the pump. Fig. 6 is a detail perspective
45 view of the removable lower end portion of
the pump barrel; and Fig. 7 is a section
taken on the line 7—7 of Fig. 2.

Referring in detail to the drawings, 5 des-
ignates a tank or reservoir, preferably of the
50 form shown in Fig. 1. This tank is con-
structed of sheet metal and may be made of
any desired capacity. The lower edge of said
tank is reinforced by a sheet iron band 6
which preferably depends below the bottom
55 of the tank. Upon this band adjacent to one
edge of the tank a wire loop 7 is hingedly

secured. Adjacent to the upper edge of the
tank a pair of similar loops 8 are secured.
To the loop 7 and one of the loops 8 a shoul-
der strap 9 is permanently attached at its
ends. A similar strap 10 is attached to the
other upper loop 8 at one end and is pro-
vided upon its other end with a hook 11
adapted to be engaged under the lower edge
of the reinforcing band 6. By means of the
straps 9 and 10, the tank or reservoir may
be conveniently strapped upon the back of
the operator. The top wall of the tank 5 is
provided with a filling opening around the
edge of which the upstanding annular flange
12 is secured. 13 designates a suitable
strainer having a handle 14 conveniently
attached thereto. This strainer is remov-
ably held within the annular flange 12 and
is provided for the purpose of straining the
insecticide as it is poured into the tank. The
filling opening is adapted to be closed by a
suitable cap or cover indicated at 15. Within
the tank 5, a pump is removably arranged.
This pump includes a cylindrical barrel 16
upon the upper end of which a plate 17 is
secured. A pipe or tube 18 is fixed in an
opening in this plate and extends through
the barrel to a point adjacent the lower end
thereof. The upper end of said pipe is lat-
erally extended and suitably provided for
the attachment of a flexible hose 18' thereto.
To the other end of this hose a pipe 19 is
adapted to be coupled, or connected, said
pipe being provided with a cut off valve 20.
The outer end of this pipe is equipped with
a suitable spraying nozzle 21. The top of
the tank 5 is also provided with an addi-
tional opening indicated at 22 which com-
municates with one side of the opening 23
through which the pump barrel 16 extends
and constitutes a continuation thereof.
Around the edges of these openings and be-
tween the wall of the tank and the plate 17
on the barrel, a gasket 24 of rubber, leather,
or other suitable material is arranged. This
gasket is provided with a series of openings
to receive the upstanding threaded bolts 25
which are suitably fixed in the tank wall.
The plate 17 is also provided with openings
to receive these bolts and upon the bolts
clamping nuts 26 are adapted to be thread-
tion within the tank.
The lower end of the pump barrel 16 is
threaded to receive a removable section 27.
A cylinder 28 arranged in vertical parallel
relation to the pump barrel is suitably se-

cured upon this removable section and a passage or conduit 28 connects the interior of said cylinder at its lower end to the base of the removable barrel section 26. Communication is afforded between the interior of the pump barrel and this conduit through the medium of a plurality of openings 29 formed in the base of the barrel section 26. To the bottom of said barrel section a stud 13 bolt 30 is secured upon which a valve disk of rubber or other flexible material shown at 31 is arranged and securely held by means of the nut 32 which is threaded upon said bolt. It will be observed that the lower end 15 of the pipe or tube 18 is disposed at one side of the center of the pump barrel and contiguous to the edge of said valve disk. In the lower end of the cylinder 27 a valve cage 33 is removably threaded, a suitable 20 packing washer 34 being arranged between the lower end of the cylinder and the body of said cage. In the valve cage a ball check valve 35 is arranged. 36 designates the pump rod which is provided upon its lower 25 end with the plunger or piston 37 which reciprocates in the cylinder 27. The pump rod extends through a tube or sleeve 38 which is provided upon its lower end with an annular flange 39 for engagement with 30 the piston. The upper end of this tube is disposed within a tubular boss 40 formed upon the plate 17. The pump rod 36 extends above the upper end of said tube and is threaded for a purpose to be later described.

The operating means for the pump includes a vertically movable bar 41 mounted in suitable guides 42 which are secured upon the wall of the tank 5. The upper end of 40 this bar is laterally extended inwardly over the tank as shown at 43 and is provided with an opening to receive the upper end of the pump rod. A nut 44 is threaded upon the pump rod and securely clamps the 45 end of the bar 41 against the upper end of the sleeve 38. A laterally projecting rod 45 is suitably secured to the reinforcing band 6 on the lower edge of the tank and upon this rod one end of the operating lever 50 46 is pivotally mounted. A link 47 is pivotally connected at its ends to said lever and to the vertically movable bar 41.

From the foregoing description, the construction of my invention and the manner 55 of its operation will be fully understood.

The insecticide solution is poured into the tank or reservoir and the filling opening then closed. After the tank has been strapped upon the back of the operator, the 60 pipe 19 is held in one hand, to direct the distribution of the solution upon the foliage of the trees or plants while the operating lever 46 is manipulated with the other hand. It will be readily understood that in the 65 upward movement of the bar 41 the piston

37 is drawn upwardly in the cylinder 27 and the solution drawn into said cylinder from the tank 5. In the downward movement of the pump piston, the ball check valve 35 is forced into its closed position 70 and the solution in said cylinder forcibly expelled therefrom through the passage or conduit 28 and upwardly through the openings 29 in the lower end section of the pump barrel. The valve disk 31 is forced upwardly and the liquid held thereby in the barrel until sufficient pressure accumulates to cause the same to move upwardly through the pipe 18. In this manner, it will be seen that the liquid is sprayed under pressure 80 from the nozzle on the end of the pipe 19, upon the foliage.

From the above description, taken in connection with the accompanying drawings, the manner of operation and several advantages of my invention will be fully and clearly understood. A large amount of the solution may be carried in the tank 5 and quickly and properly sprayed without waste. By mounting the pump within the tank in 90 the manner above explained, the same may be very easily and quickly removed therefrom and the lower end section of the pump barrel detached from the body thereof so that access may be had to the interior of 95 said barrel for the purpose of cleaning or repairing the same. The pump piston may thus also be readily repaired or the packing thereof renewed when necessary. As the tank or reservoir is constructed entirely of 100 sheet metal, it will be appreciated that the entire apparatus can be readily carried on the back of the operator without becoming burdensome. In view of the very simple construction of the invention, it is also apparent that the same will be highly efficient 105 and reliable in operation and is capable of manufacture at small cost.

While I have shown and described the particular form and construction of the several elements employed, it will be understood that the invention is susceptible of considerable modification therein and I therefore reserve the privilege of resorting to all such legitimate changes as may be 115 fairly embodied within the spirit and scope of the invention as claimed.

Having thus fully described my invention, what I desire to claim and secure by Letters Patent is:

The combination with a supply tank having an opening in its top and a detachable cover plate for said opening, of a pump including a barrel engaged at its upper end against the under side of the cover plate, a 120 piston cylinder detachably connected to the lower end of the pump barrel said connection comprising a conduit affording communication between the interior of the cylinder and the barrel, a piston to recipro- 125

cate in said cylinder having a rod, a tube movement with relation to the rod and ad- 10 surrounding said rod and engaged at its justably secure the lever in connection with lower end against the piston, means for said rod.
operating the piston including a lever re- In testimony whereof I hereunto affix my
